WATER-CEMENT RATIO CONCRETE BATCHER

Application filed July 16, 1926. Serial No. 122,837.

This invention relates to a machine for batching the ingredients which are to enter into a concrete mixture. An object of the invention is to provide apparatus for charging the mixers with successive batches of ingredients which are controlled in such a way that a constant ratio is maintained between the amounts of cement and water in each batch as well as constant ratios between the solid constituents. Another object of the machine is to economize on labor costs by providing controls which can be manipulated by a single operator. Another object of the machine is to provide a construction which will permit the taking down of a large machine for transportation in the simplest possible manner.

It has been customary among concrete workers in the past to measure with considerable care the amounts of cement, sand, and aggregates going into a charge for the concrete mixer, the ratios between these substances being determined by the use for which the concrete was intended. The amount of water to be introduced into the mixer with the charge was left more or less to the individual operator. It has been found, however, that the water content of a batch plays an important part in the characteristics of the finished concrete. The results of extended research in laboratories and in the field show that within the limits of "workability" the strength of concrete depends almost wholly upon the ratio of water to cement in the mixture, the amounts of sand and coarse aggregate being determined and kept constant within practical limits only for the purpose of controlling the characteristic of "workability," while the aggregates themselves must be composed of clean, durable particles. It is highly important therefore to maintain a constant and predetermined water-cement ratio in the batches which are put into the mixer. The actual ratio employed in any given instance will depend on the strength which will be required of the finished concrete which will be balanced against considerations of economy, since the introduction of a larger proportion of the relatively cheap aggregates into a

mixture will necessitate the addition of water to keep the mixture "workable", hence will increase the water-cement ratio and reduce the strength of the concrete.

Ignorance as to the actual controlling feature in concrete mixing which determines the strength has resulted in great uncertainty of results even in jobs where the specifications were most carefully drawn. Specifications based on a given water-cement ratio, however, are particularly advantageous to both the owner and the contractor since it makes their interests identical. With the water-cement ratio only specified, the contractor will find it to his advantage to use the largest amount of aggregates consistent with workability, thus insuring the densest and most economical concrete possible for a given strength.

It is thus necessary to maintain a constant water-cement ratio in successive batches if uniform strength is to be realized throughout the structure made of the concrete. If a certain specified strength is required, the corresponding water-cement ratio must be determined and then adhered to in batching the ingredients. For good uniform concrete work, it is also highly desirable that the ratios of sand and coarse aggregate to the cement be kept substantially constant. If dry sand were always available, the desired quantities of each ingredient could be measured for each batch and dumped into the mixer. The practical carrying out of this method of batching is, however, complicated by the fact that the sand used in concrete mixing is usually piled on the ground without shelter and is therefore liable to considerable variation in moisture content due to rain and evaporation. This variation is sufficient to affect materially the water-cement ratio of the mixture in which the sand is employed unless such moisture is allowed for. The presence of moisture also adds another complication to the operation of proportional measuring of ingredients, since it is well known that the bulk density of sand varies to a considerable extent with the percentage of moisture content, the volume of a given quantity of sand increasing with an increase of mois-

ture from bone dry up to a certain percentage, then decreasing until the volume of completely saturated sand is substantially equal to that of the bone-dry sand. Hence in measuring sand by volume, it is necessary for uniformity to maintain a substantially constant percentage of moisture. Since it is impracticable in field work to dry out the sand, the simplest way to measure it uniformly is to add water to the sand until it is nearly or wholly saturated.

By my invention, I provide apparatus for maintaining a constant predetermined water-cement ratio with ease and certainty and also for maintaining the ratios between the cement, sand and coarse aggregate constant. Briefly, I attain these ends by automatically measuring batches of cement, sand and coarse aggregate in separate measuring hoppers. As the sand enters its hopper, a predetermined quantity of water just insufficient to flood the sand is injected into the hopper with the sand. The coarse aggregate is dumped directly into the chute leading to the mixers, but the measured cement and sand are dumped into balancing hoppers which have been previously counterbalanced with weights so as to balance when the cement hopper is empty and the sand hopper holds a measure of bone-dry sand. When cement and wet sand are dumped in the respective hoppers, therefore, it is apparent that the sand itself will be counterbalanced by the weights, hence to balance the hoppers, sufficient water must be present (including the water with which the sand was wet) to offset the presence of the cement in its hopper. The actual ratio of the water to the cement will thus depend on the relative distances of their centers of gravity from the fulcrum of the balance. This is controlled by mechanism to be hereinafter fully described.

Many other advantageous features of operation and details of structure will be apparent to one skilled in the art from the disclosure of my invention in the description which follows and on the drawings, of which:

Figure 10 is a partial end elevation of the cradle for the balancing hoppers.

Figure 11 is a detail showing the pivot support of the balancing hoppers on the cradle frame.

Figure 12 is a section on the line 12—12 of Figure 11.

Figure 13 is an isometric view of the complementary parts constituting the pivot support.

Figure 14 is a section of the balancing and cradle frames taken on the line 14—14 of Figure 8.

Figure 15 is a partial plan view of a modified form of supporting frame for the balancing hoppers.

Figure 16 is a section on the line 16—16 of Figure 15.

Figure 17 is a detail view of the same.

Figure 18 is a section on the line 18—18 of Figure 16.

Figure 19 illustrates the chief principle on which the machine is based by showing diagrammatically the moments of the various elements associated with the balancing hoppers.

Referring to Figures 1 and 2 for a general description of the machine as a whole, 20 indicates a cement bin of suitable size capable of holding a considerable quantity of cement. This is separated from a sand bin 21 and a coarse aggregate bin 22 by suitable partitions arranged in such a way that the relative capacities of the three bins will be roughly proportional to the ratios of the contents as used in average construction work.

In the operation of the machine, the cement descends through a suitable aperture in the bottom of the bin 20 into a cylindrical hopper contained in a chute 23, the sand descending in a like manner into a cylindrical hopper in a chute 24. The cement and sand hoppers are designed to be rotated by suitable gearing, to be hereinafter described, and to dump their contents respectively into hoppers 25, 26, which are secured to a balancing beam which, as illustrated, may be in the form of a rockable frame 27.

The frame 27 with the hoppers 25, 26 is mounted within a cradle which comprises two circular end members 28, 29 connected by longitudinally extending bars including a pair of bulb angle side bars 30 (Figures 7 and 8) and one or more angles or channels 31.

The cradle is adapted to be rotated on its axis to dump the hoppers 25, 26 into a lower hopper 32, from which chutes 33 and 34 lead respectively into mixers 35, 36. These mixers are provided as usual with rockable scoops 37, 38 by which the batches of concrete when mixed may be educted from the respective mixers in a manner well known in the art.

The coarse aggregate bin 22 is provided with a

rockable frame 27 which is mounted on the cradle 28, 29 and which is adapted to be rotated on its axis to dump the aggregate into the lower hopper 32.

The sand bin 21 is provided with a rockable frame 27 which is mounted on the cradle 28, 29 and which is adapted to be rotated on its axis to dump the sand into the lower hopper 32.

The cement bin 20 is provided with a rockable frame 27 which is mounted on the cradle 28, 29 and which is adapted to be rotated on its axis to dump the cement into the lower hopper 32.

The coarse aggregate bin 22 is provided with a rockable frame 27 which is mounted on the cradle 28, 29 and which is adapted to be rotated on its axis to dump the aggregate into the lower hopper 32.

aggregate does not enter the balancing hoppers, but passes from the bin 22 to a measuring hopper 39 and is dumped therefrom directly into the lower hopper 32.

5   *The balancing hoppers*

The balancing hoppers 25, 26, as previously mentioned, are designed to receive respectively cement and sand from the measuring hoppers directly above them. The hopper 26 is fixed to the frame 27, the hopper 25 for the cement being slidably thereon. Its position is adjusted relatively to the balancing axis as by a threaded stud 40 secured to an 10 end of the hopper 25 (Figure 9). The stud 40 passes through an interiorly threaded hand wheel 41 which is mounted against longitudinal motion as by a flange 42 set into a suitable boss 43 secured to a circular plate 44 15 mounted against the end of the frame 27 which is adjacent to the cement hopper 25. To this plate 44 may be attached suitable counterweights 45 for a purpose to be described. Cooperating with the counterweights 45 for fine adjustment is a slideable weight 46 (Figure 4) which as shown is mounted to slide on a pair of parallel bars 47, 48 (Figure 7) and is shifted as by a threaded shaft 49 which engages an interior 20 thread on the sliding weight 46 and is rotatable as by a hand wheel 50, the bars 47, 48 preventing rotation of the weight 46 with the shaft 49 and providing support therefor. The counterweights 45 and 46 are designed 25 to balance the dry weight of the quantity of sand which is to be received in moist condition in operation as a single charge from the measuring hopper above. The sand and balancing apparatus having been balanced, 30 it is obvious that the relative weights of cement and water which will be introduced to the balancing hoppers must be in inverse ratio to the distances of the centers of their respective hoppers from the axis of balance, 35 this ratio having been converted from the ratio by volume commonly known to the art. Thus by adjusting the cement hopper 25 toward or from the axis of balance, a predetermined ratio of water to cement can easily 40 be obtained by depositing any desired quantity of cement in the hopper 25, depositing a given quantity of sand in the hopper 26 which if dry would exactly counterbalance 45 the weights 45, 46, and adding to whatever 50 moisture may be in the sand, additional water to balance the hoppers. When the hoppers are thus balanced, the moments of the sand and of the counterweights taken with the moments of the hoppers and supporting 55 elements themselves on the two sides of the balancing axis, will neutralize each other, so that the moment of the water in the sand hopper 26 and the cement in the hopper 25 will also have to balance each other. Since 60 the moment in each case is the product of the

mass by the distance of the center of gravity of the mass from the axis of balance, the relative distances of these centers of gravity from the axis will be inversely proportional to the masses of the cement and water. A 70 suitable scale 51 may be provided on one of the longitudinal bars 30 of the cradle to cooperate with an index 52 mounted on the cement hopper 25 to indicate the positions of the hopper 25 at any desired ratio converted 75 from weight to volume.

Although dry cement and well wetted sand will ordinarily slump uniformly when dumped from the measuring hoppers into the balancing hoppers so that the center of gravity of each batch of cement or wet sand after falling into its balancing hopper will be substantially the same distance from the balancing axis as the next, yet in order to provide for ingredients which may have a tendency to heap up in the hopper when dumped in from the hopper above, I may support either or both of the balancing hoppers 25, 26 pivotally on the frame 27 so as to permit them a limited rocking motion on an axis 80 transverse to the cradle. By this means, small variations in the heaping of successive batches in the hoppers 25, 26 would merely cause the hoppers to tilt on their individual axes, and as long as the amount 85 of natural tilt did not exceed the limit permitted by the apparatus, the center of gravity of each hopper with its contents would be in the vertical plane containing its rocking axis. Such a form of support is illustrated in Figures 15, 16, 17 and 18, wherein the cement hopper 25, instead of being mounted to slide in the frame 27, is swung on pivot supports 53 which are fixed to the sides of the hopper 25 and enter bearing blocks 54 90 which slide on the balancing frame 27 and are adjustably positioned therein as by a threaded shaft 40 and hand wheel 41 as previously described. The range of rocking motion of the hopper 25 may be limited as 95 by suitable extensions 55 of the pivot-bearing block 53 which engage a flange of the channel 27 when the hopper 25 is tilted to a certain angle on the pivots 53. The sand hopper 26 may also be pivotally supported as 100 by pivot members 56 bearing in suitable blocks 57 which are carried by the balancing frame 27. The pivot members 56 may be provided with extensions 55 to limit the 105 angle of tilt as previously described. 110 The frame 27 on which the hoppers 25 and 26 are directly (or, if preferred, pivotally) mounted is supported for a limited balancing motion by a pair of pivot members 60 (Figures 11-14) which are formed with suitable knife edges 61 to provide for a reasonably delicate balancing of the frame 27 and the balancing hoppers. An enclosed bearing 115 is provided to keep the knife edges 61 free from water, grit or other substances which 120

might otherwise interfere with the free action of the balance. The pivots 60 are preferably mounted on a block 62 of suitable shape which is secured by rivets, welding, or otherwise, to the frame 27, the two pivots 60 being placed accurately in line so that the axis of balance of the frame 27 is perpendicular to its length. A circular recess 63 is preferably formed in the face of the block 62 from which the pivot 60 projects, this recess being adapted to receive a flange 64 projecting from a block 65 which serves as a bearing for the pivot 60 and is secured as by bolts 66 or otherwise to each of the longitudinal frame members 30 of the cradle 28. A hole 67 is formed in the block 65 and is suitably shaped to receive the pivot 60 and to allow a limited rocking motion thereof on the edge 61, a slight lateral clearance being allowed between the pivot 60 and the side walls of the hole 67, as shown in Figure 14. The vertical dimensions of the pivot and the hole which receives it are very nearly the same, however, so that vertical play of the pivot in the hole is practically eliminated. The flange 64 and the recess 63, into which it enters, are concentric with the edge 61 so that the slight rocking motion of the frame 27 causes the flange 64 to rotate within the recess 63, but not to bind therein. As will be seen from Figure 12, the bearing block 65 is secured against the face of a cradle frame member 30 so that the pivot member 60 is thus completely protected from interference by the entry of foreign substances into the hole 67. This construction provides a pivotal support for the balancing frame carrying the balancing hoppers, which is sufficiently sensitive for the purpose desired, and at the same time provides a rugged support for the balancing hoppers as they are inverted with the cradle.

The cradle in which the balanced hoppers are carried comprises two circular end pieces 28, 29, (Figure 4), which are adapted to revolve on roller bearings 670 set in a suitably curved pair of members 671 which form part of the main frame of the apparatus. The end member 28 adjacent the cement hopper 25 is of a general angular ring shape, thus permitting free access to the weights 45 and the adjusting wheels 41 and 50. Secured to each end member 28, 29 are a pair of U-shaped members 68 (Figure 14), the ends 69 of which project into the path of an end member 271 of the balancing frame 27 and are sufficiently separated to permit a limited rocking of the frame 27, thus keeping the motion of the balancing hoppers about their balancing axis within narrow limits. The U-shaped limit members 68 are preferably mounted for vertical adjustment and for this purpose are secured to the cradle ends 28, 29 as by bolts 681 which pass through vertical slots 682 (Figure 10) and are provided

with nuts 683 to clamp the limit members 68 in adjusted position. In order to provide positive positioning means to prevent the limit members 68 from being displaced accidentally from their adjusted positions, I mount set screws 684 in suitable brackets 685 with lock nuts 686, an end of the screw 684 being adapted to engage one of the limit members 68.

In order to provide additional support for the lateral thrust of the frame 27 and the hoppers as the cradle revolves to dump the latter, I secure suitable lugs 687 to the cradle ends 28, either directly or as side pieces formed with the limit members 68. The lugs 687 are preferably located outside the side members of the frame 27 and receive the weight of the frame and the hoppers 25, 26 when the latter are turned on their sides in the course of inverting or righting. On the lower end 69 of one of the U-shaped members 68 engaging the end of the frame 27 which is adjacent the sand hopper 26, is mounted an electrical contact 70 (Figure 14) connected by a slip-ring contact and suitable wiring to a signal 71, which may be a lamp, bell or other equivalent, and to a source of energy 72, such as a battery, and grounded to the machine as at 73. The frame 27 is likewise grounded as indicated at 74 so that when sufficient weight is added to the sand hopper side of the balancing frame 27 to depress the right hand end thereof, contact is made at the point 70 which actuates an alarm signal 71 of some kind to warn the operator to shut off the water which has been flowing into the sand hopper 26. It would be a relatively easy matter to arrange an automatic cut-off for the water supply to the sand hopper 26 to be actuated when the frame 27 makes contact with the point 70, but for practical operation the signaling device is considered more desirable in that it is simpler and because it eliminates apparatus which would be liable to get out of order from the hard usage it would ordinarily receive. The end member 29 (Figures 3 and 4) of the cradle is in the form of a wheel, to the central portion of which is secured the hub 75 of a heavy gear wheel 76 by which the cradle may be successively inverted and righted to empty the balancing hoppers and to position them to receive another charge.

The measuring hoppers

Directly over the balancing hoppers 25 and 26 are the chutes 23 and 24 which contain measuring hoppers 77 and 78 to be filled with cement and sand respectively from the bins 20, 21 and to dump their contents into the balancing hoppers 25, 26 below. The hopper 77 is cylindrical in shape and is supported as by axle members 79 and 80 secured to ends thereof. The axle member 80 is also secured to an end of the sand-measuring hopper 78

which is also cylindrical in shape and disposed axially of the hopper 77. The opposite end of the hopper 78 is secured to a wheel 82 which also carries gear teeth on its periphery by which the hoppers 77 and 78 may be rotated in unison. The gear wheel 82 is provided with an axle member 821 projecting from the hub member 81 by which it is supported in a suitable bearing formed in a bracket 822 secured to the main frame of the machine. The chutes 23 and 24 which contain the hoppers 77 and 78 each have an opening upward into their respective supply bins 20, 21, and another opening below, through which cement and sand are discharged into the balancing hoppers 25, 26. The openings in the bins 20, 21 are shaped to register with the open tops of the hoppers 77, 78 when the latter are in righted position, the rims of the bin openings being adapted to conform closely to the cylindrical shape of the hoppers so that the openings are closed off by the cylindrical walls of the hoppers when the latter are inverted.

5 The chute 24 may be made cylindrical in form to hold the cylindrical hopper 78 with a slight clearance between their respective walls. To keep the space between the chute and hopper clean, longitudinal wipers 780 (Figure 3) may be formed or secured on the outer surface of the hopper 24 to sweep the interior surface of the chute 24. Within the supply bins 20 and 21 and directly over the measuring hoppers are mounted agitators designed to stir up the cement and sand adjacent the openings and to prevent arching of these materials thereover. These agitators may be of any desired construction. As shown, they comprise a series of blades 83 mounted on a common shaft 84 near an end of which is fixed a gear wheel 85 by which the agitators may be driven. The measuring hopper 77 is preferably built to receive a given quantity of dry cement suitable for the size of the machine constructed. The amount of cement therefor supplied for each batch of concrete is fixed for any one machine. In order to be able to vary the proportion of sand and cement, the sand hopper is constructed with means for adjusting the capacity thereof. These means as illustrated in Figure 6 comprise a movable end wall or bulkhead 86 having a wide tapered peripheral flange 87 fitted closely within the cylindrical wall of the hopper 78. The bulkhead 86 is preferably supplied with a boss 88 which is bored axially and is internally threaded to receive a screw shaft 89 which projects inwardly from the hub 81 and is supported in a recess therein, being retained in place as by a set screw 90, the end of which enters a peripheral groove 91 permitting the screw shaft 89 to be turned with reference to the hub 81. Also threaded on the shaft 89 is a lock nut to secure the end mem-

ber 86 in adjusted position. This lock nut comprises a hand wheel 92 which bears against an inner bulkhead 93 on which is a tapering flange 94 which fits the complementary taper inside of the flange 87. Rotation of the hand wheel 92 in the proper direction will push the bulkhead 93 to the left and expand by wedging action the flange 87 against the wall of the hopper 78, thus making a water-tight end to the hopper. Longitudinal adjustment of the bulkhead 86 may be made by loosening the hand wheel 92, thereby permitting the inner bulkhead 93 to move to the right and releasing the flange 87. Rotation of the shaft 89 by a hand wheel 95 fixed thereon will cause the bulkhead 86 to move in or out and thereby to decrease or increase the capacity of the measuring hopper 78. When the bulkhead 86 is in the position desired, rotation of the hand wheel 92 will move the inner bulkhead 93 to the left and expand the flange 87 tightly against the walls of the hopper 78.

10 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

15 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

20 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

25 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

30 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

35 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

40 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

45 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

50 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

55 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

60 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

65 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

70 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

75 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

80 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

85 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

90 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

95 The measuring hopper 39 for the coarse aggregate is also preferably constructed with an adjustable end bulkhead to permit the variation of the capacity of the hopper. The construction of the adjustable bulkhead may be similar to that illustrated in Figure 6, or it may be simplified by omitting the flange-expanding member 93 since it is not necessary that the hopper 39 be watertight.

100 **Water supply**

Water may be supplied to any suitable connection such as a pipe 96 (Figure 1), this supply pipe being provided with suitable branches to carry water to the various points where it is needed. One branch 97 leads to a two-way flushometer valve 98 by the manipulation of which a measured quantity of water, say one gallon, may be supplied to either of the concrete mixers 35, 36. This charge of water is customarily introduced into concrete mixers immediately in advance of a batch of materials and serves as a washing charge to wet the interior of the mixer and to prevent any of the batch of materials from sticking to the inside thereof. This measured quantity of water, which is regulated by the action of the flushometer valve, is allowed for in adjusting the counterweights of the balancing frame 27. Another branch 99 of the water-feed line is controlled as by a quick action shut-off valve 100 and supplies water directly to the balancing said hopper. When a charge of sand is introduced into the sand hopper 26 in the normal operation of the machine, it will be outweighed by the charge of cement introduced into the hopper 25 plus the counter-balancing weights 45, 46. The operator thereupon opens the valve 100 and allows water to flow through the pipe 99 into the sand hopper 26.

until the balancing frame 27 is tilted, closing the contact 70 and giving the warning signal to the operator who thereupon promptly closes the valve 100.

6 A third branch 101 passes through a quick action shut-off valve 102 and is led upwardly through a suitable flushometer valve 103 (Figure 3) to a suitable discharge 104 which is placed at the opening in the bottom of the sand bin 21 directly over the measuring hopper 78. The valve 102 is for emergency use and to shut off the supply to the sand bin when the machine is shut down after the day's run. The valve 103 is preferably connected with the gear 82 as by a suitable pitman 105 which connects the valve arm 106 with a crank 107 mounted on the axle 821. Each time the sand hopper 78 is rotated into upright position to receive a charge of sand from the storage bin 21, the flushometer valve 103 is opened to permit a predetermined quantity of water to flow through the discharge member 104 into the hopper 78 with the sand which falls through from the bin to fill the hopper. The flushometer valve is 20 adjusted to supply a quantity of water which will nearly, but not completely, flood the charge of sand which is received from the bin by the hopper 78. It is desirable to use 25 water in this manner to saturate the sand in order to secure uniformity in the actual quantities of sand measured out by volume, it being well known that partially moistened sand varies considerably in volume density. 30 It is also, however, desirable to avoid a complete flooding of the sand inasmuch as this would require water-tighting between the hopper 78 and the chute 24, which would add materially to the construction cost of the apparatus and would require wearing parts 35 which would have to be periodically replaced.

Driving mechanism

40 Power for driving the machine may be supplied from any suitable source. As shown, an electric motor 108 is mounted on the main frame of the machine in a suitable position and has connected therewith a drive shaft 109 on which is fixed a worm 110. The 45 motor is intended to operate continuously during the operation of the machine, and through the worm 110, which meshes with a worm ring gear 111 fixed on the mixer 36, to drive this mixer at a constant speed. A ring 50 gear 112 may be mounted on the mixer 36 to mesh with a suitable gear 113 by which a shaft 114 is driven which extends across the machine and carries at its further end another gear similar to 113, the latter meshing 55 with a ring gear 115 mounted on the mixer 35. Thus both the mixers 35 and 36 are driven together at equal speeds. The worm 110 is also adapted to mesh with a worm gear 60 116 which is formed with a toothless sector 117 of sufficient size to clear the worm 110.

Thus when the sector 117 registers with the worm 110, the gear 116 is not rotated. When the gear 116 is turned slightly to mesh with the gear 110, it is rotated thereby through one revolution and then automatically stops. 70 The worm gear 116 is preferably mounted on a suitably supported shaft 118 which may be connected as by a clutch 119 of suitable construction to a gear 120 which meshes with the gear wheel 76 and another gear wheel 121 75 of equal size which is secured to the coarse aggregate measuring hopper 39. The gears 76 and 121 are just twice the size of the gear 120 so that one complete revolution of the gear 120 will cause half a revolution of the gears 76 and 121. As will be seen in Figure 80 3, the gear wheel 82 which is secured to the cement and sand-measuring hoppers is in mesh with the gear 76 which rotates the balancing hoppers, these gears being of equal 85 size so that half a revolution of one will result in half of a revolution of the other. The balancing hoppers and the measuring hoppers for sand and cement are so related that when one set is upright, the other set is inverted, and the relation of these hoppers to the worm gear 116 is such that when the toothless sector 117 is registering with the worm 110, all the hoppers in the machine are either directly upright or completely inverted. 90 The clutch 119, if incorporated in the machine, must be of a kind which positively locks its inter-engaging parts in one relative position only to maintain in operation 95 the correct relation between the hoppers and the toothless sector 117. A clutch at this point, however, is not essential and may be omitted. The coarse aggregate hopper 39 is related to the balancing hoppers 25, 26 in such a way that these three hoppers are all 100 upright or inverted together. 105

The operation of the machine is controlled through the five hand levers illustrated in Figure 1. As shown, the middle lever 122 may be connected by means of a bell crank 110 arm 123 and a suitable link or cable 124 with a lever 125 which carries on its axis a loose pinion 126 meshing with the gear wheel 76. A suitable pawl 127 is mounted on the lever 125 and is positioned to engage in the teeth 115 of the pinion 126. Operation of the lever 122 will cause the lever 125 to rock and turn the pinion 126 through the engagement of the pawl 127. This rotation of the pinion 126 is communicated through the gear wheel 76 120 to the gear 120 and the worm gear 116, the result being that the worm gear 116 is moved into meshing relation with the driven worm 110, whereupon the worm gear 116 is driven by the worm 110 through one complete revolution, this resulting, as previously described, in one-half revolution simultaneously of the gear wheels 76, 82 and 121, whereby the balancing hoppers 25, 26 and the coarse aggregate hopper 39 are inverted, while the meas- 125

uring hoppers 77, 78 are righted, or vice versa. The hand levers 128, 129 are connected by a suitable cable 130 with a sheave 131 mounted on the axis of a flap valve 132 which may be rocked to open the chute 33 and close the chute 34, or to open the chute 34 and close the chute 33, whereby a charge materials from the movable hoppers above may be directed either into the mixer 35 or the mixer 36. The flap valve 132 enables the operator to direct successive charges alternately into the two mixers 35, 36, or if preferred one mixer alone can be used. Hand levers 133, 134 may be connected respectively by suitable cables 135, 136 to lever arms 137, 138, which are mounted to rock respectively with the scoops 37, 38 to cause a mixture to be discharged from the mixer 35 or 36. As will be seen from Figure 1, all the controls for the machine are placed within easy reach of a single operator and are designed to be easily manipulated by him.

Before starting the actual operation of the machine, the bulkhead 86 is first adjusted 25 in the sand-measuring hopper 78 to measure the amount of sand predetermined by characteristics of workability which will have the desired ratio to the fixed quantity of cement which constitutes a charge of the cement hopper 77. In like manner, the capacity of the coarse aggregate hopper 39 is adjusted as desired. A charge of moist sand is then measured in the hopper 78 and is removed therefrom and thoroughly dried. This charge of 30 dried sand is then placed in the balancing hopper 26. The movable balancing hopper 25 is then adjusted longitudinally so that the pointer 53 is opposite the number on the scale 51 indicating the desired water-cement 35 ratio. The counterweights 45 and 46 are then adjusted to balance the hoppers 25, 26 with the charge of dry sand in the latter. The 40 flushometer valve 103 is adjusted to supply a quantity of water commensurate with the adjusted capacity of the sand-measuring hopper 78. The dry sand is removed from the hopper 26 (as by inverting the balancing hoppers) and the machine is thereupon ready 45 for operation. The three supply bins 20, 21 and 22 having been filled, the cement and sand descend into the measuring hoppers 77 and 78 which are upright, filling them. At 50 this stage, the balancing hoppers 25 and 26 and the coarse aggregate hopper 39 are inverted. The hand lever 122 is then rocked, bringing the teeth of the worm gear 116 into mesh with the worm 110. The gear 116 thereupon makes one revolution turning the balancing hopper and the coarse aggregate hopper 55 into upright position and at the same time inverting the measuring hoppers 77, 78. During this half rotation of the hoppers, the charges of cement and sand which have been received by the measuring hoppers are emp- 60 tied into the respective balancing hoppers

and at this point the coarse aggregate hopper is also in position to receive a charge from the supply bin 22. The valve 100 is thereupon opened and water is allowed to flow into the sand hopper 26 until the balancing frame is tilted to close the contact 70 75 80 85 90 95 100 105 110 115 120 125 130 frame is tilted to close the contact 70 and actuate the signal 71, whereupon the operator closes the water valve 100 and opens the flushometer valve 98 to discharge into one mixer or the other a quantity of wash water as previously described, the flap valve 132 being positioned to open the chute leading into the mixer into which the wash water is delivered. The moments of the various weights which result in the balancing of the hoppers 25, 26 are diagrammatically illustrated in Figure 19. This figure also shows clearly the purpose of the various steps in the adjustment and operation of the balance outlined in the foregoing description. The operator now rocks the hand lever 122 again with the result that the balancing hoppers 25, 26 and the coarse aggregate hopper 39 are simultaneously inverted, dumping their contents into the lower hopper 32 and thence into one of the mixers 35, 36, which are revolving at a constant speed. This charge contains measured quantities of all the ingredients necessary to make up the batch of concrete. The water content in the batch is, by means of the apparatus previously described, in a predetermined fixed ratio to the cement in the batch, so that the strength of the concrete produced from the mixer can be accurately determined and controlled, the water ratio values of succeeding batches being practically identical. As the balancing hoppers are inverted, the sand and cement measuring hoppers are righted and as they reach their upright position, the flushometer valve 103 is opened so that a charge of sand mingled with sufficient water to nearly saturate it descends into the measuring hopper 78, while a charge of cement descends into the hopper 77. This completes one cycle of operations which may be repeated indefinitely.

The framework supporting the various parts of the apparatus has not been described in detail. It is made as light and strong as possible in view of the hard usage to which mechanism of this kind is liable to get. A machine of this type large enough to handle "two-bag" mixes of concrete (i. e. where each batch of cement is the equivalent of two bags or 188 pounds, and the aggregates are in desired proportion to this quantity of cement) is of considerable size and cannot easily be transported in one piece from one job to another. I therefore prefer to make the apparatus in two or more sections which can be set up and bolted together, and afterwards taken down for transportation. A machine of the "two-bag" size if separated into two sections on a horizontal plane at the bottom

of the storage bins, can be loaded readily on two flat cars with an ordinary construction crane. This line of division leaves all the working parts in place and permits a simple and rapid assembling for operation on a new location. If desired, the apparatus can readily be made so as to be taken down into smaller sections.

Having thus described an embodiment of my invention, it should be evident to those skilled in the art that many changes and modifications may be made therein without departing from its spirit or scope as defined by the appended claims.

15 I claim:

1. In a concrete batching machine, a frame, means mounted on said frame for measuring pre-determined volumes of two solid ingredients, one of which may be wet, means mounted on said frame in a position to receive charges of said ingredients from said measuring means and to balance the dry ingredient against the water with the wet ingredient; said balancing means including counterweights counterbalancing the dry weight of the wet ingredient, and means for adding water to that originally with the wet ingredient to make a total water content sufficient to counterbalance the dry ingredient.

2. In a concrete batching machine, a frame, means mounted on said frame for measuring for successive batches predetermined volumes of cement and wet sand, means for weighing the cement against the wet sand mounted on said frame in a position to receive measured volumes of cement and wet sand from said measuring means, and means for increasing the water content of the wet sand sufficiently to balance the cement, said weighing means having adjustably fixed counterweights counterbalancing the dry weight of the sand.

3. In a concrete batching machine, a frame, means mounted on said frame for measuring for successive batches predetermined volumes of cement and wet sand, means for weighing the cement against the wet sand carried by said frame in a position to receive measured volumes of cement and wet sand from said measuring means, said weighing means including counterweights to counterbalance the dry weight of the sand, means for adding water to that originally with the wet sand, and means for indicating when the total quantity of water with the sand bears a predetermined ratio to the measured quantity of cement.

4. In a concrete batching machine, a pair of measuring hoppers for cement and damp sand respectively, the sand hopper having means for variably adjusting its cubic capacity, a balancing beam, a pair of balancing hoppers supported by said beam beneath the respective measuring hoppers to receive cement and sand therefrom, and counterweights

adjustable to counterbalance the dry weight of the measured sand.

5. In a concrete batching machine, means for measuring predetermined volumes of cement, sand, and coarse aggregate for successive batches, means for reducing the sand as measured to standard bulk density, and means for obtaining a substantially constant water-cement ratio in successive batches regardless of the moisture in the sand as measured.

6. In a concrete batching machine, a balancing frame, pivotal supports for said frame, a hopper mounted on said frame on either side of said pivotal supports, one of said hoppers being adjustable toward or away from said supports, and variable counterweights mounted on said frame.

7. In a concrete-batching machine, a balancing frame, pivotal supports for said frame, a hopper mounted on said frame on either side of said pivotal supports, one of said hoppers being adjustable toward or away from said supports, means for supplying material to one of said hoppers to counterbalance material previously placed in the other hopper, a signal, and means for operating said signal when the hoppers are balanced.

8. In a concrete batching machine, a balancing frame, a hopper fixed to said frame adjacent one end thereof, a second hopper mounted on said frame adjacent the opposite end thereof for longitudinal adjustment thereon, pivot members secured to said frame between said hoppers permitting said frame to rock on a transverse axis through said pivots, means for limiting the range of rocking motion of the frame, and counterweights supported by said frame adjacent to one of said hoppers.

9. In a concrete batching machine, a cradle comprising a frame mounted for rotation on its longitudinal axis, a rockable frame pivotally supported within said cradle for rocking motion on a transverse axis, stop members on said cradle for limiting the rocking motion of the rockable frame, and a pair of hoppers mounted on said rockable frame adjacent the opposite ends thereof, one of said hoppers being adjustable toward or away from the rocking axis.

10. In a concrete batching machine, a cradle comprising a frame, circular end members fixed to said frame, means for supporting said cradle for rotation about its longitudinal axis, a rockable frame pivotally supported by said cradle frame for rocking on a transverse axis, a sand-receiving hopper fixed to said rockable shaft adjacent one end thereof, a cement-receiving hopper adjacent the opposite end of the rockable frame and on the opposite side of said transverse axis, said cement-receiving hopper being adjustable toward or away from said trans-

verse axis, counterweights supported by said frame adjacent the cement-receiving hopper, means for supplying predetermined quantities of cement and sand to their respective hoppers, means for supplying water to the sand hopper, and means for rotating said cradle on its axis with the apparatus carried thereby.

11. In a concrete-batching machine, a hopper mounted for rotation to assume successively upright and inverted positions, driving means for rotating said hopper, and means for effecting a limited operative connection between said driving means and said hopper for a single change of position thereof, said connecting means comprising a gear operatively associated with said hopper, said gear having a toothless segment, a member associated with said driving means and engageable with said gear to rotate said hopper, said member being disengaged from said gear when opposite to a toothless segment thereof, and means for moving said gear into engagement with said member.

12. In a concrete-batching machine, a plurality of hoppers, each being rotatably mounted to assume successively upright and inverted positions, means operatively connecting said hoppers together for simultaneous rotation, and means for effecting a limited rotation of said hoppers from one of said positions to the other, said hopper-rotating means comprising a shaft, gearing connecting said hoppers with said shaft in two to one ratio whereby the angle of rotation of each hopper is half that of the shaft, a worm gear mounted on said shaft, said worm gear having a toothless segment, a constantly driven worm engageable with said

worm gear for driving connection with said hoppers, said worm being disengaged from said worm gear when opposite the toothless segment, and means for moving said worm gear into meshing engagement with said worm.

13. In a concrete-batching machine, a pair of measuring hoppers coaxially mounted for simultaneous rotation on a horizontal axis, a pair of balancing hoppers disposed respectively beneath said measuring hoppers, said balancing hoppers being mounted for rotation on a horizontal axis and geared to said measuring hoppers for equal simultaneous rotation therewith, the gearing being such that when either pair of hoppers are upright, the other pair are inverted, a power driven member, means actuatable to effect a limited connection between said hoppers and said power driven member whereby the hoppers are rotated one half a turn only, means for delivering predetermined quantities of water to one of said measuring hoppers, said delivering means comprising a water-supply pipe, a flushometer valve in said pipe, and means for opening said valve when said measuring

hopper is rotated to upright position, means for supplying water to one of said weighing hoppers, a signal, and means for operating said signal when sufficient water has been supplied to said weighing hopper to bring the total water content thereof to a predetermined weight.

14. In a concrete-batching machine, a pair of concrete mixers, means for rotating said mixers, delivery chutes movable into position to remove the contents of the rotating mixers, feed chutes leading into the mixers, a receiving hopper communicating with the upper ends of said feed chutes, a valve member between said receiving hopper and feed chutes, means for measuring out predetermined volumes of cement and sand, means for supplying a quantity of water to the sand sufficient to make the total weight of water which is mixed with the sand bear a predetermined ratio to the weight of the measured cement, means for dumping the measured cement, sand, and water into said receiving hopper, means for controlling the movements of said delivery chutes, means for controlling said valve member, means for controlling said measuring means, and means for controlling said water supply, all said controlling means being located within reach of a single operator.

15. The step in batching cement, damp sand and water for a concrete mixture which comprises counterbalancing the dry weight of a batch of sand and weighing a batch of cement against an amount of water to be mixed therewith having a predetermined weight ratio to the cement and including the original moisture in the sand and water added thereto.

16. The steps in batching cement, damp sand and water for a concrete mixture which comprise counterbalancing the dry weight of a batch of sand; measuring a batch of cement by volume, and weighing the measured cement against a quantity of water to be mixed therewith having a predetermined weight ratio to the cement and including the original moisture in the sand and water added thereto.

17. The steps in batching cement, damp sand and water for a concrete mixture having a predetermined water-cement ratio, which comprise measuring a fixed amount of water for washing the mixer which is to receive the ingredients of the mixture, introducing the washing water independently into the mixer, measuring a batch of cement by volume, placing the measured cement on one side of a balance and the damp sand on the other side of said balance, the centers of gravity of the cement and damp sand having respective distances from the fulcrum of the balance in a ratio substantially equal to said water-cement ratio, counterweighting on the cement side of the balance for the moment

of the dry weight of the sand about the fulcrum of the balance diminished by the moment of the washing water independently supplied to the mixer, adding to the damp sand sufficient additional water to balance the opposed moments of cement, counterweights, sand, and water, and bringing together said balanced cement, sand, and water and said washing water.

10 18. The steps in batching ingredients for a concrete mixture which comprise measuring batches of cement and wet sand by volume, balancing said batches with counterweights and water added to the wet sand whereby the moments of the dry weight of the sand and of the counterweights are equal and opposite, and the moments of the cement and of the water associated with the sand are equal and opposite.

15 19. The steps in batching ingredients for a concrete mixture, which comprise measuring batches of cement and wet sand to have a predetermined ratio by volume, counterweighting the dry weight of the sand, and adding sufficient water to that already with the sand to make the total quantity of water with the sand bear a predetermined ratio by weight to the batch of cement.

20 20. The steps in batching ingredients for concrete which comprise measuring a batch of sand, drying said sand, balancing said sand and the portion of the balancing apparatus on one side of the balancing axis against counterweights and the portion of the balancing apparatus on the other side, measuring a batch of cement, supporting said cement on the side of said axis opposite to the sand, and re-balancing the apparatus by adding water to the sand.

25 21. The steps in the method of batching ingredients for a concrete mixture, which comprise measuring by volume batches of two of said ingredients, then weighing the measured batches against each other and adding water to one of them to bring it and the water therewith up to predetermined weight relative to the other.

In testimony whereof I have affixed my signature.

50 PAUL J. HALLORAN.
